UNITED STATES PATENT OFFICE.

WILLIAM H. THOMPSON, OF BURBANK, OHIO.

WASHING MACHINE.

Application filed May 11, 1922. Serial No. 560,233.

To all whom it may concern:

Be it known that I, WILLIAM H. THOMPSON, a citizen of the United States, residing at Burbank, in the county of Wayne and State of Ohio, have invented certain new and useful Improvements in Washing Machines, of which the following is a specification.

My invention relates to improvements in washing machines, the present embodiment of the invention relating more particularly to that class or type in which a washing cylinder of open formation is rotatably mounted in a relatively fixed body or casing forming a suitable receptacle for the washing or cleansing liquid within which the cylinder is adapted to rotate.

The invention further relates to that class or type in which suitable movable plunger members are provided with vacuum creating devices or cups adapted to move against and press the clothes to be washed and then move away from the same to create a partial vacuum or suction action, the improved washer being adapted to combine the functions of the ordinary cylinder washer with those of the ordinary "clothes pounder" type.

The primary object of the invention is to provide a generally improved washing machine of the type or class indicated which will be exceedingly simple in construction, cheap of manufacture and efficient in use.

A still further and very important object is the provision of oppositely arranged vacuum creating pistons in a washing cylinder adapted to be simultaneously moved toward and from each other to successively press and create a partial vacuum in the interposed clothes batch within the washing cylinder with each complete stroke or reciprocation of the pistons or plungers.

A still further object is the provision of improved means for simultaneously driving or rotating the washing cylinder and reciprocating the pistons during the rotation of such cylinder.

With the above mentioned and other ends in view, the invention consists in the novel construction, arrangement and combination of parts, hereinafter described, illustrated in one of its embodiments in the accompanying drawings and particularly pointed out in the appended claims.

Referring to the drawings, forming a part of this specification, Figure 1 is a side elevation, partly in section, of a washing ma-

chine constructed in accordance with this invention, the clothes pressing and vacuum creating pistons being at their innermost positions or the inner ends of their inward working strokes preparatory to being moved in an opposite direction or away from each other for producing a partial vacuum or suction in the interposed clothes in the washing cylinder.

Fig. 2, an enlarged central longitudinal sectional view of the washing cylinder, detached, the pistons being in their extreme outward positions or ends of their vacuum creating working strokes.

Fig. 3, a fragmentary cross sectional view of the washing cylinder, some of the cylinder forming slats being removed for the purpose of clearer illustration of the parts.

Fig. 4, a similar view of one of the reciprocatory clothes pressing and vacuum creating pistons or heads, detached from the washing cylinder.

Fig. 5, a plan view of the washing cylinder door or closure section, detached.

Fig. 6, an enlarged plan view, partly in section, of one of the piston stems connecting and actuating yokes and the rotary piston actuating or driving member therefor, the dotted lines indicating the relative position of the parts in the extreme opposite end of the working stroke or position thereof.

Similar numerals of reference designate like parts throughout all the figures of the drawings.

The improved machine comprises a suitable casing or housing 1, forming a receptacle for the washing liquid and within which the washing cylinder of open formation is adapted to rotate, as hereinafter referred to. The casing or housing 1, is mounted on a suitable frame or support, the latter being provided with suitable supporting legs or columns 1^a. The top of the relatively fixed casing or housing 1 is provided with a suitable opening adapted to be opened and closed through a suitable door or closure member 1^b, affording access to the interior of the washing cylinder, as hereinafter referred to.

The washing cylinder is of open formation, the outer periphery, in the present instance, being made up of a plurality of suitably spaced slats or strips 2^a, connected at their ends to cylinder heads 2, the latter being provided with trunnions 2^b, rotatably mounted in suitable bearing openings in the

casing or housing ends or heads 1^c. The outer periphery of the cylinder may be made up of any suitable foraminous material and, in the present instance, the spaced slats 2^a are 5 of triangular shape in cross section adapted to fit into similarly shaped notches 2^c, (see Fig. 3) on the outer peripheries of the head 2. As a means of providing access to the interior of the washing cylinder the latter is 10 provided with a door or closure section made up of a plurality of slats or strips 2^d, provided with connecting cross members 2^e, as shown most clearly in Fig. 5 of the drawings.

15 As a means of driving or rotating the washing cylinder one of the trunnions 2^b is provided with a gear wheel 3, meshing with a pinion 4, carried on a power shaft 5, the latter, in the present instance, being provided 20 with a sprocket wheel, adapted to be driven by means of a sprocket chain 6, leading to a sprocket wheel on a motor shaft 7, of a motor 8.

As a means of combining with the ordinary washing cylinder function of the ordinary washing machine of this type the functions of the washer of the "clothes pounder" type; and particularly as a means of providing vacuum or suction creating 25 devices in opposed relation and engaging the batch of clothes on opposite sides as rotated within the washing cylinder, the latter is provided with longitudinally movable vacuum creating pistons or plunger 30 heads 9, movable longitudinally of the axis of the washing cylinder, said pistons or heads 9 being provided with suitable vacuum or suction creating devices adapted to engage opposite portions of the clothes 35 batch when moved inwardly toward each other and to create a partial vacuum when moved outwardly away from each other. In the present instance, such vacuum or suction creating devices are in the specific 40 form of funnel or cup shaped members 9^a, having their open or flaring ends extending toward each other and preferably arranged in opposed relation to each other. The smaller ends of the cup members 9^a are 45 mounted in suitable openings in the plunger heads 9, the openings in the cups 9^a being provided with valve members 9^b, provided with stem members 9^c, the valve heads 9^b being adapted to rest on valve seats 9^d, of 50 the cups 9^a when the latter are drawn rearwardly in the partial vacuum creating reciprocation thereof with respect to the interposed batch of clothes.

As a means of limiting the outward or 55 open movement of the valves 9^b, the valve stems 9^c may be provided with stop projections 9^e, adapted to engage with the neck portions of the cups as the latter are moved toward each other whereby the cups are 60 open in operation of engaging and pressing

the opposite portions of the clothes batch. The clothes pressing and vacuum creating pistons 9 and cups 9^a are spaced apart a suitable distance to provide an intermediate clothes washing chamber 10, and as a means 70 of simultaneously reciprocating the pistons 9, the latter are provided with piston stems 9^f, extending through suitable openings 2^f, in the trunnions 2^b (the latter being preferably of tubular formation as shown), the 75 outer ends of the piston stems 9^f preferably terminating in heads 9^g, detachably and rotatably mounted in bearing sockets 11^a, of yoke members 11, the sockets 11^a being 80 closed by means of threaded caps 11^b. As 85 a means of preventing the rotation of the yoke members 11, the latter are provided with guide stems 11^c, extending through guide or bearing heads 12^a, of bearing brackets 12, extending outwardly from the 90 ends of the washer supporting frame, the gearing for actuating the pistons and piston stems being preferably enclosed in a protecting casing 13, at each end, as shown 95 most clearly in Fig. 1 of the drawings. As the piston stem connecting and actuating yokes and the gearing mechanism therefor are alike and arranged in opposed relation to each other in the end casings 13, one set of yoke and gear mechanism need only be 100 shown and described.

As a means of actuating each yoke 11 and the connected pistons simultaneously with the rotation of the washing cylinder, each bracket 12 is provided with a vertical driving shaft 14, carried in a horizontal bracket 12^b, at its top, each shaft 14 being provided with an arm 14^a, adapted to rotate within the yoke 11 and to reciprocate the latter as shown in Fig. 6 of the drawings. 105 Each shaft 14 receives its motion from a bevel gear 15, meshing with a second bevel gear 16, on the adjacent end of the driving shaft 5. The guide stem 11^c is provided with a key or spline 11^d, adapted to operate 110 in a guide recess in the adjacent bearing head 12^a of the bearing bracket 12.

The term "vacuum" as used herein is a relative term meaning a partial vacuum and the term "vacuum" is used synonymously with the term "suction" and such term as used in the appended claims are to be construed and treated accordingly. 115

Having thus described one of the embodiments of my invention, without having attempted to set forth all the forms in which it may be made, or all the modes of its use, what I claim and desire to secure by Letters Patent is,—

1. In a washing machine, a cylinder provided with reciprocatory piston heads having valved cups extending toward each other and adapted to be moved toward and from each other as the cylinder is rotated. 125
2. In a washing machine, in combination 130

with a washing cylinder of open formation including heads provided with bearing elements; of pistons having valved vacuum creating cups movable toward and from each other longitudinally of said cylinder, and means for reciprocating said pistons.

3. A washing machine, comprising a casing, a washing cylinder of open formation rotatably mounted therein, piston heads 10 in said cylinder movable longitudinally therein toward and from each other, vacuum creating devices carried by said pistons and adapted to engage the clothes to be washed as moved toward each other and 15 to create suction therein as moved from each other as the cylinder is rotated, means for rotating said cylinder in said casing, and means for simultaneously moving said piston heads toward and from each other as 20 the cylinder is rotated.

4. In a washing machine, a support in-

cluding a housing forming a washing receptacle, a cylinder in said receptacle provided with bearing elements extending through said housing, clothes pressing and 25 vacuum creating pistons in said cylinder adapted to simultaneously move toward and from each other forming an intervening clothes washing chamber, said pistons being provided with piston stems extending 30 through said bearing elements, a gear wheel on one of said bearing elements for rotating said cylinder, a power shaft provided with a pinion meshing with said gear wheel, and gearing between said power shaft and 35 said piston stems for reciprocating the latter and said pistons in synchronous relation.

In testimony whereof I have affixed my signature.

WILLIAM H. THOMPSON.
